UNITED STATES PATENT OFFICE.

SILAS M. HESS, OF BLOOMSBURG, PENNSYLVANIA.

CULM-BAR.

SPECIFICATION forming part of Letters Patent No. 325,837, dated September 8, 1885.

Application filed May 6, 1885. (No model.)

To all whom it may concern:

Be it known that I, SILAS M. HESS, of Bloomsburg, Columbia county, Pennsylvania, have invented a new and Improved Culm-Bar, 5 of which the following is a full, clear, and exact description.

The object of my invention is to provide a new and improved bar for burning culm, which bar is so constructed that the parts that have 10 been burnt out can be easily replaced by others.

The invention consists in the combination, 15 with parallel supporting-bars united in pairs, of flat perforated sections placed upon said bars and serving to receive the culm.

Reference is to be had to the accompanying drawings, forming part of this specification, in which similar letters of reference indicate corresponding parts in all the figures.

20 Figure 1 is a plan view of my improved culm-bar. Fig. 2 is a side and sectional view on the line $x-x$, Fig. 1. Fig. 3 is a cross sectional elevation of the same on the line $y-y$, Fig. 1.

25 Two cooling-bars, A, placed parallel and having their top and bottom edges curved downward from the ends to the middle, are united by the end pieces, B, and the curved cross-pieces C or arches, all cast integral.

30 The sections D, provided with perforations, have downwardly-projecting lugs F, which fit between the bars A, and the said lugs have wings G on the sides, the said wings resting on the top edges of the bars A.

The outer ends of the end sections, D, rest 35 upon the end pieces, B, which are shouldered, as shown.

A series of the above-described united bars and their perforated sections are placed together, and the culm to be burned is placed 40 on the perforated sections D.

The advantages of the above-described culm-bar are that the cooling-bars do not get hot enough to burn out, and in case one of the sections D burns out it can be replaced very 45 easily and an entire new bar is not required.

The lugs on the sections and the cross-pieces uniting the bars A hold the sections D securely in place.

Having thus described my invention, I claim 50 as new and desire to secure by Letters Patent—

1. A culm-bar consisting of two parallel bars united by cross-pieces and perforated sections placed longitudinally of the parallel bars and provided on their under sides with 55 transverse lugs, the lugs of each section fitting between two cross-pieces of parallel bars, substantially as set forth.

2. The combination, with the bars A, united by cross-pieces C, of the perforated sections 60 D, having lugs F, provided with wings G, substantially as herein shown and described.

SILAS M. HESS.
